UNITED STATES PATENT OFFICE.

JOSEF JULIUSBURGER, OF BERLIN, GERMANY.

MACHINE FOR UNTWISTING AND CARDING FIBROUS MATERIALS.

Application filed June 20, 1928, Serial No. 286,779, and in Germany July 2, 1927.

The raw fibres for the manufacture of upholstering material, especially the so-called vegetable horse hair, are generally placed on the market in the form of rope-like twisted hanks which for the purpose of the further treatment are untwisted and carded.

My invention relates to a machine which effects the untwisting and carding in one operation.

Preferred embodiments of my invention are illustrated in the accompanying drawings, wherein

Fig. 1 is a side elevation,

Fig. 2 a rear elevation and

Fig. 3 a front elevation of the machine.

Fig. 4 is the side elevation opposite to that of Fig. 1.

Fig. 5 represents in a larger scale an axial section of a rotary head through which the hank is untwisted.

Fig. 6 is a more enlarged axial section of the rotary head.

Fig. 7 is a corresponding side elevation at right angles to Fig. 6.

Fig. 8 is a partial side elevation corresponding to Fig. 1.

Fig. 9 is a side elevation of a toothed comb cooperating with the rotary head.

Fig. 10 shows the toothed comb from below.

Fig. 11 is a schematic section of the front part of the machine.

Fig. 12 is a side elevation corresponding to that of Fig. 4 of a machine which is provided with an auxiliary mechanism for working up waste fibres.

Fig. 13 is a vertical section according to the line 13—13 of Fig. 12.

Fig. 14 represents a modification of the rotary head in an axial section.

The frame for the untwisting and carding machine proper is a casing 1 in the upper part of which the driving motor 2 is mounted. The front part of the shaft of this motor is elongated (in Fig. 1 towards the right) and bears a pulley 3, a fan 4 and a rotary head 5. The pulley 3 and the fan 4 form a single casting the parts of which are coherent at their hubs. The said casting is flanged at 9 to the rotary head 5. Between the pulley 3 and the fan 4 there is a separating wall and between the fan 4 and the rotary head 5 a sieve-like wall 7 is provided.

The rotary head 5 extends with its free

front end into a circular aperture 10 of the 55 front wall 10^a of the casing (Fig. 5). According to the preferred embodiment of the invention illustrated in the drawing the rotary head consists of an outer jacket 11 in which a sleeve 12 is detachably inserted. The 60 said sleeve is hollow-shaped like a blast-pipe and provided with a front flange 13 which fits into a corresponding boring in the outer jacket 11. On its rear end the sleeve 11 is provided with a stud 17 fitting into a central 65 bore of the jacket 11 and being connected with the latter by means of a screw 18. The cavity of the sleeve grows wider towards its free end like a funnel and extends from its free end towards its inner end at first in an axial direction, then turns outwards with a slight curvature in such a way that the outlet mouth at the inner end of the cavity is in a plane forming an acute angle with the axis of the rotary head and being placed on the periphery of the sleeve in a radial distance from its axis. Opposite to this mouth a correspondingly shaped circular aperture is provided in the jacket 11. The rotary head proper as well as the sleeve is made of a light metal 70 such as aluminum. Both the inner orifices are protected by special steel rings 15, 15^a to avoid wear of the edges of the orifices. The ring 15 of the sleeve 12 is inserted into a bore of an extension of the said sleeve and detachably connected with this extension by 75 means of screws 16 (Fig. 7). After loosening the screws the ring 15 may be turned. In this way the wear is equally distributed over the ring so that it may be used for a 80 rather long time, before it must be replaced. The ring 15^a is also connected with the jacket 11 by means of screws 16^a.

The rotary head is located in a partition 45 of the casing. The said rear wall of the 95 partition is formed by the grating 7 and towards one side of the machine the partition has a cap-like extension 46 (Fig. 2) which is open on its lower side at 47 so that the material worked up may fall out downwards.

The partition 45 is provided on its top with a flap-door 20 (Figs. 3, 9, 10 and 11) on the lower side of which hackle or carding teeth 19 are provided being located opposite to the outlet mouth of the rotary head. The hackle or carding teeth are fastened to a plate 19^a which is rotatably mounted on the cover 20 by means of a stud 19^b.

By means of the lever 22 the cover 20 may be swung about the axis 21 and brought into different angular positions and by tightening of a winged screw 23 a bolt extending transversely through the partition 45 and being provided with clamping projections is axially displaced to clamp the cover 20 in different angular positions. In this way the distance between the hackle or carding teeth and the rotary head may be adjusted. The rotary arrangement of the carrier 19 allows some yielding movement of the teeth 19 under the influence of the fibres being whirled towards the teeth through the action of the rotary head.

The supply of the hank is effected by means of two superimposed rollers 24 and 25 the lower one of which 24 is driven from the motor 2. The roller 24 and a worm wheel 27 are keyed to a shaft 26 which is mounted in the front part of the frame of the machine. The worm wheel is in mesh with a worm 28 keyed to a shaft 29 to which also a pulley 30 is fastened being connected by means of a belt 31 with the pulley 3 fixed to the motor shaft. The upper roller 25 is mounted between the limbs of a frame 32 which by means of a shaft 33 being mounted in the front wall of the box is suspended so as to be capable of being oscillated.

The shaft 33 is provided on one of its ends with an arm 34 which is bent off at a right angle and provided with a set screw 35 through which the lever 34 leans upon the front wall of the casing. The other end of the shaft 33 is bent to form a crank arm 36 which is connected with a pedal 38 by means of a rod 37. By means of this pedal the frame 32 bearing the roller 25 may be lifted (Fig. 8). For fixing the frame in its lifted position a ratchet lever 39 is provided. The lower roller 24 is provided with five or another plurality of longitudinal ribs intersected by grooves so that the cross-section of the roller is a star with five points (Figs. 1 and 8). The grooves are cut out for the reception of the thickenings of the hank, whilst the ribs are adapted to take the hank along. The upper roller 25 is provided with a helical rib. The interstices between the several portions of the helical rib are groove-like shaped. On the ends of the roller 25 flange-shaped weights 25^a are provided.

The space between the walls 6 and 7 (Fig. 1) is communicating downwards with a chamber 42 in the box-like frame of the machine. From the rear of said box a pipe 43 leads into the open air. Through this pipe the air which is loaded with dust is ejected by means of the fan 4. The wall from which the pipe 43 extends is provided with an opening which is closed by means of a side-plate 44. The machine is easily to be transported on handles 61.

In Figs. 12 and 13 an auxiliary device is

illustrated through which waste fibrous material is worked up. Such waste-material is obtained in upholstering workshops in which the machine is employed. The auxiliary device allows the machine as specified to be also used for working up the said waste-material. The device consists of a funnel 60 which laterally enters into the space 45. In the interior of the said funnel two superimposed rollers 56, 57 are provided. The cross-sections of the said rollers may conform to that of the roller 24, and the lower roller may be driven in the direction of the arrow as illustrated in Fig. 13. For this purpose a worm-wheel 56^a being in mesh with a worm 55 is keyed to the shaft of the said roller. On the worm-shaft 54 a pulley 52 is keyed which is connected by means of a belt 51 with a pulley 50 keyed to the shaft 26 which is driven from the motor 2 by means of the worm-gear 27, 28. The connection of the funnel 60 with the box-like frame is effected by flanges 63 which extend upwards and downwards into horizontal notches 64 of the wall of the frame. The said notches are adapted to take up a closing slide-plate during the normal working of the machine.

If the machine is used for working up loose fibrous material the rotary head 5 is replaced by a special head 58 which is provided with willowing teeth 59. The fibrous material fed to the funnel 60 is transported through the rollers 56, 57 to the revolving willowing teeth 59 and carded by the said revolving teeth.

The working of the machine is as follows: After lifting the upper roller 25 the hank A to be worked up is pushed through the free orifice of the rotary head 5 into the central cavity of the same so that the hank projects through the outlet mouth of the rotary head. By releasing the ratchet lever 39 the roller 25 is then lowered to seize the hank. The amount of lowering of the roller may be regulated by means of a set-screw (Fig. 3). As soon as the driving motor is set going the spiral of the hank is canceled through the rotary motion of the rotary head, so that the untwisted end of the hank passes through the outlet mouth of the rotary head into the space 45 and is here whirled towards the hackling or carding teeth 19 and transformed thereby into a loose material which is thrown out through the cap 46. The said material may be collected in containers which are placed below said cap. Thereby the dust is sucked up through the sieve 7 by the action of the fan 4 and brought together with short fibrous material to the chamber 45 from which the air may escape through the pipe 43. The helical shape of the rib of the upper feeding roller 25 has the purpose of working against the tendency of the hank to be displaced towards one side corresponding to its spiral when being fed into the rotary

head. The effect of the spiral is canceled by the effect of the screw so that with a pitch of the screw corresponding to the feeding velocity the hank remains in the middle of 5 the cavity of the rotary head.

For working up hanks of different diameters several sleeves 12 are provided the hank guides of which are of different widths. The outer shape of the several sleeves is the same 10 so that they all fit into the outer jacket 11 of the rotary head. Also by adjusting the carrier 19 for the hackling teeth 19 an accommodation to the material to be worked up may be effected. The distance of the 15 teeth 19 from the rotary head is altered by a corresponding adjustment of the angular position of the cover 20.

The cavity of the rotary head may also be shaped as shown in Fig. 14 wherein the cavity 20 has the shape of a bore ending in an enlarged central orifice at the free end of the rotary head and extending towards its inner end in a substantially straight line forming an acute angle with the axis of the revolving head. The outlet mouth of the cavity of the rotary head is opposite to the hackling teeth.

I claim:—

1. In a machine for untwisting and carding hanks, a rotary head, a nozzle in said head for guiding the hank to be untwisted, said nozzle having an axially disposed inlet portion and a main portion turning outwards from the axis of rotation of the head 35 with an acute angle to an outlet mouth.

2. In a machine for untwisting and carding hanks, a rotary head, a nozzle in said head for guiding the hank to be untwisted, said nozzle extending from the inlet inside 40 at first in an axial direction, then passing over with a slight curvature to an outlet portion which turns outwards from the axis of rotation of the head with an acute angle.

3. In a machine for untwisting and carding hanks, a rotary head, an outer jacket forming part of said rotary head, and an exchangeable inner sleeve adapted to be inserted into said outer jacket and having a nozzle for guiding the hank to be untwisted, 50 said nozzle having an axially disposed inlet portion and a main portion turning outwards from the axis of rotation of the head with an acute angle to an outlet mouth.

4. In a machine for untwisting and carding hanks, a rotary head, a nozzle in said head for guiding the hank to be untwisted, said nozzle having an axially disposed inlet portion and a main portion turning outwards from the axis of rotation of the head with 55 an acute angle to an outlet mouth, and carding teeth being provided opposite to said outlet mouth of the nozzle.

5. In a machine for untwisting and carding hanks, a rotary head, a nozzle in said head for guiding the hank to be untwisted, 60

said nozzle having an axially disposed inlet portion and a main portion turning outwards from the axis of rotation with an acute angle to an outlet mouth, and a steel ring for the protection of the edges of the head encircling 70 said outlet mouth of the nozzle.

6. In a machine for untwisting and carding hanks, a rotary head, an outer jacket forming part of said rotary head, and an exchangeable inner sleeve adapted to be inserted into said outer jacket and having a nozzle for guiding the hank to be untwisted, 75 said nozzle having an axially disposed inlet portion and a main portion turning outwards from the axis of rotation of the head with an acute angle to an outlet mouth, and steel rings encircling said outlet mouth, such rings serving for the protection of both the outer jacket and the inner sleeve.

7. In a machine for untwisting and carding hanks, a rotary head, a nozzle in said head for guiding the hank to be untwisted, said nozzle having an axially disposed inlet portion and a main portion turning outwards from the axis of rotation of the head with an acute angle to an outlet mouth, and a pair of feed rollers being arranged in front of said rotary head, and means for lifting the upper roller and fixing the same in the lifted position. 95

8. In a machine for untwisting and carding hanks, a rotary head, a nozzle in said head for guiding the hank to be untwisted, said nozzle having an axially disposed inlet portion and a main portion turning outwards from the axis of rotation of the head with an acute angle to an outlet mouth, and a feed roller of helical form being arranged in front of said rotary head. 100

9. In a machine for untwisting and carding fibrous hanks, a casing, a rotary head mounted on said casing, a nozzle in said head for guiding the hank to be untwisted said nozzle having an axially disposed inlet portion and a main portion turning outwards from the axis of rotation of the head with an acute angle to an outlet mouth, a blower lodged in a compartment of the said casing, a sieve separating the said compartment from the rotary head, and a dust chamber communicating with the said blower and the open air. 110

10. In a machine for untwisting and carding hanks, a rotary head, a nozzle in said head for guiding the hank to be untwisted, said nozzle having an axially disposed inlet portion and a main portion turning outwards from the axis of rotation of the head with an acute angle to an outlet mouth, and carding teeth being provided opposite to said outlet 120 mouth of the nozzle, said teeth being mounted on a rotatable carrier. 125

11. In a machine for untwisting and carding hanks, a rotary head, a nozzle in said head for guiding the hank to be untwisted, said 130

- nozzle having an axially disposed inlet portion and a main portion turning outwards from the axis of rotation of the head with an acute angle to an outlet mouth, carding teeth being provided opposite to said outlet mouth of the nozzle, and means to regulate the distance between said teeth and said rotary head.
12. In a machine for untwisting and carding hanks, a rotary head, a nozzle in said head for guiding the hank to be untwisted, said nozzle having an axially disposed inlet portion and a main portion turning outwards from the axis of rotation of the head with an acute angle to an outlet mouth, carding teeth being provided opposite to said outlet mouth of the nozzle and mounted on an angularly
- adjustable plate, and means to set said plate in different angular positions.
13. In a machine for untwisting and carding hanks, a rotary head, a nozzle in said head for guiding the hank to be untwisted, said nozzle having an axially disposed inlet portion and a main portion turning outwards from the axis of rotation of the head with an acute angle to an outlet mouth, carding teeth being provided opposite to said outlet mouth of the nozzle, and two superimposed feeding rollers in front of said rotary head, one of said rollers having a corrugated surface, the other roller being of helical form.

In testimony whereof I affix my signature.

JOSEF JULIUSBURGER.
